(57) **CLAIM**

The ornamental design for a built-in coffee maker, as shown and described.

DESCRIPTION

FIG. 1 is a front perspective view of a built-in coffee maker according to a first embodiment of my new ornamental design;

FIG. 2 is a front view thereof;

FIG. 3 is a top view thereof;

FIG. 4 is a right side view thereof, with the left side view thereof being a mirror image thereof;

FIG. 5 is a bottom perspective view thereof;

FIG. 6 is a cross sectional view taken along lines 6-6 of FIG. 2;

FIG. 7 is a cross sectional view taken along lines 7-7 of FIG. 2;

FIG. 8 is a front perspective view of a built-in coffee maker according to a second embodiment of my new ornamental design;

FIG. 9 is a front view thereof;

FIG. 10 is a top view thereof;

FIG. 11 is a right side view thereof, with the left side view thereof being a mirror image thereof;

FIG. 12 is a cross sectional view taken along lines 12-12 of FIG. 9; and,

FIG. 13 is a cross sectional view taken along lines 13-13 of FIG. 9.

The broken lines represent environment or structure of the built-in coffee maker and do not form any part of the claimed design.

The rear view of the built-in coffee maker is not ornamented and is therefore not shown.
